MACHINE FOR BINDING WREATHS

Hans Ludvig Nielsen, Copenhagen, Denmark

Application June 14, 1950, Serial No. 167,964
In Denmark March 18, 1944

7 Claims. (Cl. 41—3)

1

This invention relates to machines for binding wreaths of straw or the like fibrous material such as, for instance used as base for wreaths of the kind used at funerals, on church-yards or the like.

It is the object of the invention to provide a machine for producing such wreaths of uniform and different sizes in rational mass production.

A further object of the invention is to provide a machine of the kind referred to, which is simple and reliable in operation.

Still a further object is to provide a machine of this kind, which can easily be adjusted to produce wreaths of different sizes.

Still a further object of the invention is to provide a machine, which is simple in construction and easy in operation.

With these and other objects in view the invention will now be described in detail with reference to the accompanying drawing in which:

Fig. 1 is a perspective plan view of a machine according to the invention,

Fig. 2 is a perspective fragmentary view of the left hand front part of the machine shown in Fig. 1 in another embodiment,

Fig. 3 is a vertical sectional view thru a part of the table of the machine shown in Fig. 1 taken along the line 3—3 in Fig. 1,

Fig. 4 is a fragmentary sectional view showing on a larger scale a detail of the driving mechanism for the rotating ring shown in Figs. 1 and 3, and taken on line 4—4 of Fig. 3,

Fig. 5 is a fragmentary plan view of part of the driving mechanism for the three driving rollers shown in Fig. 1 behind the vertical ring, with the table plate removed,

Fig. 6 is a fragmentary vertical sectional view corresponding to that shown in Fig. 3 with the top part of the vertical ring omitted and a showing instead of the rollers,

Fig. 7 is a fragmentary sectional view showing a detail of the driving mechanism shown in Fig. 5 taken in the direction of the arrow 7 of Fig. 5,

Fig. 8 is a large scale perspective view showing the details of the wire holder shown in Fig. 1 on the vertical ring,

Fig. 9 is a perspective fragmentary sectional view of the driving mechanism shown in Fig. 5 seen from the under side of the machine table,

Fig. 10 is a large scale fragmentary elevational view of the driving mechanism for one of the three rollers shown in Figs. 5 and 6,

Fig. 11 is a vertical section of the mechanism shown in Fig. 10 along the line 11—11 in Fig. 10,

Fig. 12 is a perspective view of another embodiment

2

ment of the driving mechanism shown in Fig. 9 seen from the bottom,

Fig. 13 is a large scale elevational view, partly in section, illustrating another detail of a driving mechanism for the vertical ring shown in Figs. 1 and 3,

Fig. 14 is a fragmentary large scale vertical sectional view thru one of the three rollers showing its arrangement relatively to the surface of the table,

Fig. 15 is a side view of the outer guide for the wreath shown on the top of the table in Fig. 1,

Fig. 16 is a plan view of the guide shown in Fig. 15,

Fig. 17 is a large scale vertical sectional view thru one of the guide rollers along the line 17—17 in Fig. 16 in a large scale,

Fig. 18 is a diagrammatic sectional view of the table showing the arrangement of the driving motor,

Fig. 19 is a perspective fragmentary view of the machine shown in Fig. 1 with the ring and rollers omitted and showing another embodiment of the guides,

Fig. 20 is a side elevational view of a set of feeding funnels,

Fig. 21 is a plan view of a set of guides,

Fig. 22 is a side elevational view of a set of rollers,

Fig. 23 is a perspective fragmentary view of the machine showing how the straw is fed thru the guides during the binding of a wreath, and

Fig. 24 is a fractional perspective view of a modified embodiment of the roller driving mechanism shown from below.

In the following description equal parts of the different figures are referred to by equal reference numerals. The base of the machine is the table 20 as shown in Fig. 1 having at each corner 40 a leg, of which only the three legs 22, 24 and 26 are shown in Fig. 1.

In the table an aperture generally referred to as 28 and more clearly shown in Fig. 19 is provided. The central part 30 of the aperture is

rather narrow, but near the ends the aperture has enlarged portions 32 and 34 respectively, extending behind the rear edge 36 of the narrow portion 30, but leaving the front edge 38 of the aperture substantially linear along its whole length. Adjacent the front edge 38 of the aperture a pivotable arm generally referred to as 46 is arranged. This arm is at its one end 50 by means of a pin 52 hingedly connected to a small hinge plate 54 secured to the top surface of the table by means of screws, rivets or the like 56.

Near the middle the pivotable arm 48 has an arcuate portion 53 formed as a funnel and having its widest opening 69 towards the front edge 62 of the table.

Adjacent the left side enlarged portion 32 of the aperture 28 an arcuate arm 64 is secured to the top surface of the table 20 near the hinge plate 54. This arm may be secured by welding in case of the table being constructed wholly by metal, or it may be secured by screws from the bottom side of the table or in any other convenient manner. On the top of the pivotable arm 48 a hook 66 (Fig. 3) is arranged, in which one end of a helical spring 68 engages. The other end of this spring 68 is secured to an arm 70 of a U-shaped member 72 having another arm 74 extending from the top of the arcuate arm 64 and secured thereto for inst. as shown in Fig. 3 by means of a screw 76. Adjacent the front edge 78 of the arm 48 a rectangular small aperture 80 is provided in the table surface. Thru this aperture 80 a pivotable pawl or hook 82 extends adapted to snap over the end 78 of the arm 48 by a projecting hook portion 84 having an inclined surface 86, as best shown in Fig. 3. The hook 82 is formed as a two-armed lever 88, 90 mounted on a bracket 92 secured to the underside of the table by means of screws 94 or the like. A screw or the like 96 allows the hook arm 90 to swing. The lower part of the hook arm 90 is of enlarged diameter at 98 and is provided with a central hole 100. As shown in Fig. 9 this hole 100 provides a passage for a pin or rod 102 that projects on the end of a pivotable arm 104 arranged under the table substantially parallel with the surface thereof and adapted to swing about the pin 106. The pin 106 extends from the end of another pin 108 serving as a distance element to keep the lever 104 in position in spaced relationship to the table. The free end of the rod 102 is at its end provided with a stop member 110 and is surrounded by a spring 112 abutting with its one end against the portion of enlarged diameter 98 and with its other end against the stop member 110 thus serving to keep the hook 82 in the position shown in Figs. 1 and 19 engaging the end 78 of the arm 48 to keep it in alignment with the table surface against the lifting action of the spring 68.

Adjacent the front edge 62 of the table 20 a screen or guide 114 (Figs. 1, 2, 19 and 23) is arranged extending from near the left hand front corner of the table to the left side of the funnel opening 60. This screen for instance is made of metal plate and has secured thereto near the middle at its lower edge a rectangular extending arm 116, which is clamped against the table surface to keep the screen 114 upright and in the position shown. To effect this clamping a screw or bolt 118 (Fig. 19) is provided on the surface of the table to receive a clamping member 120 having a long arm 122 and a short arm 124 enabling it to hold the arm 116 in position by means of a wing nut 126. Extending from the right hand side of the funnel opening 60 a similar screen or guide 128 (Fig. 1) is arranged. This screen or guide 128 is substantially arcuate, forming a part of a cylinder having its other end 130 (Fig. 19) terminating at a distance from the rear edge 36 of the aperture 28, substantially opposite the right hand side of the narrow funnel opening of the funnel 58. The guide 128 is provided with vertical arms 132 and 134 at its lower edge. These arms extend

inwardly towards a center of the cylinder and serve the purpose of securing the screen 128 to the table surface by means of clamping members 136 and 138 together with wing nuts 140 and 142 in a similar manner as described in connection with the screen 114.

Concentric with the guiding member 128 another guiding member 144 is arranged (Figs. 1 and 16) having its left hand end 146 substantially opposite the left hand side of the narrow opening of the funnel 58 in spaced relationship thereto. This guiding member 128, details of which are shown in Figs. 15, 16 and 17, consists of two spaced arcuate L-shaped rails 148 and 150 (Fig. 17) between which a plurality of rollers 152 are arranged. Each roller has a central bore 154 for the passage of a pin 158 as shown in detail in Fig. 17. The ends of the pins may be riveted at 160 and 162 or in another way secured to the L-shaped arcuate rails to enable free rotation of the rollers. The lower rail 150 is provided with outwardly extending vertical arms 164, 166 and 168 (Figs. 7 and 16) to be clamped against the top surface of the table by screws 170 carrying wing nuts 172 and 174 and clamping members 176, 178 and 180 in a similar manner as the guiding member 128. As seen in Fig. 1 the annular space between the two guiding members 128 and 144 is hereby left unobstructed. The right hand edge of the guiding member 144 is provided with a pivotable plate 182, which at 184 is hingedly connected to the ends of the two rails 148 and 150, and which is influenced by a spring 186 having its one end 35 abutting against the vertical flange of the rail 148 and its other end abutting against the outer surface of the plate 182. The spring may as indicated have a few or a single turn 188 (Fig. 16) wound round an elongated outwardly extending portion 190 of the last of the pins 158.

The arcuate arm 64 extends with an other arcuate portion 192 under the table 20 (Figs. 3 and 18). This portion is semi-circular and is at its removed end 194 secured to the under side 45 of the table. As shown in Fig. 3 the two portions 64 and 192 form a part of a circle, which underneath the table bridges the aperture 28 from one end thereof to the other and above the table partly extends over said aperture. The 50 arcuate member 64, 192 serves as support for guiding members for a ring member 196 rotatably arranged substantially concentric with the arcuate member 64, 192.

To support the ring member 196 a plurality 55 of rollers are arranged extending inwardly from the arcuate member 64, 192. In the embodiment shown in Fig. 3 there are provided three such roller members. The two lower roller members 198, 200 respectively are arranged freely rotatable 60 on the end of each of two radial arms 202 and 204 respectively, each provided with longitudinal slots 206 and 208 respectively to enable adjustment in radial direction. The arms 202 and 204 are secured and kept in position by means of 65 screws or the like 210 and 212 respectively. Between the two rollers 198 and 200 a further roller 214, the arrangement of which is shown in Figs. 3 and 6, and illustrated more detailed in Fig. 4, is arranged. This roller 214, the shape of which 70 corresponds to the three other supporting rollers, has a cylindrical portion 216 with rims 218 and 220 respectively, to guide the rotatable ring 196 and preventing it from escaping in sideward direction from the support. The roller 214 is by means of a pin 222 and ball bearings, of which 75

only one, 224, is shown in the section of Fig. 4, arranged between two pivotable arms 226 and 228 on each side of the ring member 192 and secured thereto by means of a pin 230. The other ends of the two arms 226 and 228 are also connected by means of a pin 232, the central part of which 234 is of slightly larger diameter than the end parts in order to keep the two arms 226 and 228 in spaced relationship parallel to each other. The central part is further provided with a groove 236 for the attachment of a spring 238, the other end of which is secured to a hook 240 (Fig. 3) on the lower surface of the table 20 and urging the roller 214 to engage the outer periphery of the ring member 196.

On the top side 64 of the supporting member 64, 192 a corresponding third supporting roller 242 is arranged on the inner end of a radial arm 244 having a longitudinal slot 246 to enable a radial movement guided by screws 76 and 248, the screw 76 serving also the purpose of holding the U-shaped member 70, 72, 74. The arm 244 extends outside the arcuate member 64 and is at its top end provided with sidewardly bent portions 250 (Figs. 1 and 3) terminating in small tubular members 252 receiving screw threaded hooks 254 each connected with a spring 256 and 258 respectively the other ends of which are connected with each of the two arms 70 and 74, the springs thus pressing the roller 242 in radial direction to engage the outer surface of the rotatable ring member 196 to keep the same also in engagement with the rollers 198 and 200. The top ends of the screw threaded hooks 254 are provided with nuts 260 to enable easy and simple adjustment of the resilient pressure of the roller 242. It will be appreciated that the diameter of the cylindrical part of the four rollers 198, 200, 214 and 242 must be slightly less than the annular space between the rotatable ring 196 and the supporting member 64, 192.

To effect the rotation of the ring 196 and thereby the operation of the machine an electric motor 262 is provided and suspended in the manner diagrammatically shown in Fig. 18. The motor is arranged on a plate 264, which by means of hinges 266 is carried on the transverse bar 268 between the two legs 24 and 26 of the table (Fig. 1). On this bar also an electric switch 270 is arranged, one side of which by means of a cable 272 is connected to the supply means and the other side of which by a cable 274 is connected to the motor circuit. From a pulley 276 on the motor an endless belt 278 is arranged over another pulley 280 (Figs. 3, 6, 13 and 18) on the end of a pivotable lever 282 carried by the supporting member 192 by means of a pin 284. The length of the belt 278 is so adjusted that the motor and its base plate 264 will be in the slightly inclined position substantially as shown in Fig. 18.

The arrangement of the parts is more detailed shown in Fig. 13. The right hand part 286 of the lever 282 is as shown in section in Fig. 13 provided with a parallel lever 288 arranged on the other side of the member 192 and carried by the pin 284. A distance member 290 serves to keep lever arm 286 in spaced relation to the member 192 substantially parallel therewith and a similar distance member 292 serves the same purpose with respect to the arm 288. The pulley 280 is secured to a rotatable shaft 294 supported by roller bearings, of which only one 296 is shown in section in Fig. 13. The pulley 280 is arranged adjacent the lever arm 286 laterally of the mem-

ber 192. Also secured to the rotatable shaft 294 a driving roller 298 is provided arranged opposite the interior periphery of the member 192 between this and the ring 196. The other lever arm 300 of the lever 282 is connected to a tension spring 302 the other end of which is secured to a hook 304 (Fig. 3) mounted on the lower surface of the table, thus urging the lever 282 to pivot about the pin 284 with the driving roller 298 releasing the ring 196. To prevent the driving roller to engage the stationary supporting member 192 during the rotation, a stop member 306 (Figs. 3 and 6) is provided on the front side of the member 192 to limit the movement of the lever arm 286 in direction away from the ring 196.

The lever arm 300, as best shown in Fig. 1, extends thru an elongated aperture 308 in a plate 310 secured to the table leg 22 and arranged substantially perpendicular to the arm 300. At the free end the lever arm 300 is provided with a handle 312. The lower end of the aperture 308 is provided with a lateral extension 314 limited in upward direction by an abutment surface 316, under which the lever 300 can be locked by pressing down the handle 312 corresponding to an engagement between the driving roller 298 and the ring 196.

Behind the aperture 28 in the table 20 seen from the front edge 62 thereof and referring now to Fig. 19, three apertures 318, 320 and 322 are provided. The two apertures 318 and 320 are of substantially circular form and arranged in alignment substantially perpendicular to the edge 36 of the aperture 28 located substantially opposite the left hand side of the narrow opening of the funnel 58. The aperture 322 is elongated or curved having its center in the neighbourhood of the edge 36 and located in such a manner that it extends with its left hand end substantially opposite the right hand side of the narrow opening of the funnel 58.

In these three apertures driving rollers 324, 326 and 328 (Fig. 1) respectively are arranged mounted for rotatable movement. Details of the arrangement of one of these rollers, namely the roller 324, mounted in the aperture 318, are shown in Fig. 14 showing in part a section thru the roller 324. The roller is of substantially hyperbolic form having its smallest diameter at 330 slightly above the table surface. The diameter is larger at the top 332 than at the foot 334. At the bottom the roller has a substantially circular disc shaped foot portion 336 of slightly smaller diameter than the diameter of the aperture 318. Along the major part of its length the roller has vertical projecting ribs, 338, distributed round the surface in spaced relationship. These ribs start from the foot portion 336 and terminate either as shown under the top or extend the whole way up. Thru the roller 324 an axial hole 340 is provided for the passage of a spindle or shaft 342. The shaft is arranged in bearings 344, 346 in two plates 348 and 350 arranged in spaced relationship and also spaced from the bottom side of the table 20 (Figs. 7, 9 and 14). A cross pin or the like 352 is arranged thru the shaft 342 and engages a cross aperture 354 in the lower side of the foot portion 336 of the roller 324 to enable the roller to rotate with the shaft and simultaneously supporting the roller in the position shown with the top surface of the foot portion 336 substantially in the same plane as the table surface. It will be understood that this support and driving

connection within the limits of the invention can be made in any other convenient manner so as for instance by a square disc or the like connected with the shaft 342 and received in a square aperture in the bottom of the foot portion 336 of the roller. The top of the shaft is screw-threaded at 356 and the roller 324 is provided with a wing nut 358 enabling the roller easily to be mounted or detached.

Between the two plates 348 and 350 a pinion 360 is arranged adapted to set the roller in rotation.

In Figs. 5 and 6 where the driving mechanism for the rollers are shown in detail the pinions for the two other rollers 326 and 328 are designated 380 and 390 respectively and wing nuts 378 and 388 respectively and the shafts by 356 and 386 respectively.

As shown in Fig. 4 the shaft 222 is connected with a universal joint 400, which is the same as shown in the front part of Fig. 5, and which is also shown in Fig. 6 with reference to the explanation of the operation of the driving mechanism. It will be understood that the shaft 222 and thereby also the driving mechanism, which will now be described in the following will be actuated by the cooperation of the roller 214 (Figs. 4, 5 and 6) with the outer arcuate surface of the ring 196.

The other end of the universal joint 400 is connected to one end of a shaft or spindle 402, the other end of which is connected to a further universal joint 404 (Figs. 5 and 6), which in turn is connected to still another spindle 406 (Fig. 5) mounted in a bearing 408 arranged under the table and carried thereby by means of an arm 410 extending from the lower plate 350 of the two plates shown in Fig. 14, see also Fig. 9. The end of the shaft 406 on the other side of the bearing 408 is provided with a circular disc 412 (Figs. 5, 6 and 7) having a radial slot 414 (Fig. 7), in which is secured by means of a screw or the like 416 one end of an arm or rod 418. The connection is arranged in such a manner that the arm or rod 418 acts as a crank lever having its crank arm adjustable by adjusting the position of the screw 416 in the slot 414. At the end of the arm 418 a further universal joint 420 (Figs. 5, 6 and 7) is arranged connected to one end of a further rod 422, which again carries a universal joint 424 connected with one end of still a further rod 426.

As it will be understood the rotation of the roller 214 (Figs. 3 and 4), by engaging the surface of the ring 196 will cause transmission of a movement resulting in an axial reciprocating and oscillating movement of the rod 426 (Fig. 5). As shown in Fig. 14 the spindle 342 extends thru the lower bearing 346 with a portion designated 428, as shown in Fig. 6. The rod 426 thus making a combined reciprocating and oscillating movement is connected with the lower portion 428 of the spindle 342, by means of a ratchet gear mechanism, the details of which are shown in Figs. 10 and 11. This gear mechanism comprises a ratchet wheel 430 secured to the shaft portion 428 and arranged between the two bifurcated portions 432 and 434 of a fork member 436 connected to the end of the rod 426 for instance as shown by having its screw threaded end 438 screwed in a hole 440. The rear side of the bifurcated portions is along part of its length closed by a member having on its interior side a recess 444 adapted to support one end of a spring 446, the other end of which engages a recess 448 in a

pivotal ratchet lever 450 pivotably mounted on a pin 452 so as to have its other end 454 engaged with the teeth of the ratchet wheel 430.

It will be understood that this mechanism during the combined oscillating and reciprocating movement of the arm 426 will act as a ratchet wrench imparting upon the shaft portion 428 a step by step movement in direction of the arrow in Fig. 5.

10 The arrangement of the two pinions 360 (Figs. 5, 6 and 14) and 380 (Fig. 5) with appertaining rollers 324 and 326 between the two plates 348 and 350 is more detailed shown in Fig. 9 where for the sake of clearness the pinions have been omitted. The two plates 348 and 350 form the top and bottom plate respectively of a square-like box having ends 456 and 458 secured under the table for instance by means of four screws designed 460, 462, 464 and 466 respectively, as shown in Fig. 5. The end portion 456 has a triangular extension 468 carrying at its top a bearing 470 for a double link lever 472, 474, which is connected to another double link lever or link 476, 478. The joint of the two links is designed by 480. The upper lever 472 is extended beyond the bearing 472 at 482, see also Fig. 1 and is at its free end provided with a handle 484. The other end of the said other link lever 476, 478 is connected by means of a pin 486 (Fig. 5) 20 with a pair of spaced triangular plates 488, 490. The other ends of these triangular plates are supported for swinging movement by a pin 492 on a projection portion 494 of the other end portion 458. The other end of the lever 104 is 25 by means of a pin 496 connected to the third top 498 of the lower triangular plate 490. The third roller 328 (Fig. 5) with appertaining pinion 390 is carried by the two triangular plates 488 and 490 with the pinion arranged between these 30 plates in the same horizontal plane as the two other pinions 360 and 380. As readily understood from the drawing the movement of the handle 484 (Fig. 1) in horizontal plan in direction towards the edge 62 of the table 20 in direction of the arrow shown in Fig. 5 will cause the double plate triangle 488, 490 to pivot about the pin 492, see Fig. 5 to bring the pinion 390 to mesh with the two other pinions 360 and 380 to cause all three rollers to be rotated intermittently 35 under the influence of the driving mechanism 40 in direction of the arrow indicated in Fig. 5.

The handle lever 482 may be locked in a slotted plate extending below the side edge of the table (not shown) in a similar manner as 45 the handle lever 316 was locked. Upon release of the handle and moving it in counterclockwise direction the link movement will cause the triangular double plate 488, 490 to move in direction of the arrow shown right thereto in Fig. 5 to 50 disengage the pinions and thereby stop the rotation of the three rollers. The end portion 456 (Fig. 9) has a perpendicular extension 457 provided at its end with an abutment 459 to limit the movement of the triangular plate. This 55 abutment may be supported by a central screw connecting it to the underside of the table.

As indicated in Fig. 1 a spool 508 provided with winding wire 502 is arranged on an arm 504 extending laterally behind the rotatably mounted ring 196. The two enlarged portions 32 and 34 of the aperture 28 serve the purpose of allowing this spool to pass thru the table during the rotation of the ring. Adjacent the spool on the interior of the ring 196 a small bracket 506 (Fig. 3) is mounted carrying a pin 508 having

at its end a guiding hole 510 for the passage of the end of the wire 502 and preferably spaced from the end a small bushing 512 with a further guiding hole 514 for the wire.

The details of the spool and its arrangement is shown in enlarged scale in Fig. 8. The arm 594 has a short portion 516 screw threaded at its end at 518 to enable its attachment to the ring 196 by screwing it into a hole 520 (Figs. 1 and 3) therein. Substantially perpendicular to the portion 516 a long portion 522 is arranged bifurcated at 524 at its end and carries here pivotably about a short pin 526 an arm 528 adapted either to form a cross bar or having its one end lying between the two forked portions to be in alignment with the rod 522. Near the bent portion between the long and the short portion a ring 530 is secured to the long portion 522 or in other manner, limited in its movement towards the bent portion, for instance by mounting near the ring 530 a pin (not shown) traversing the long portion 522. Against this ring 530 one end of a spring 532 is abutting. At the other end of the spring 532 a further loose ring 534 is provided serving as abutment for the lower flange 536 of the spool 500. The other flange 538 of the spool consists merely of a round disc loosely mounted on the rod 522. Also loosely mounted on the long portion 522 between the disc 538 and the pivoted arm 528 is a bushing 540 having a plurality of diametrically opposite slots 542, 544 and 546 extending from the right hand end surface in varying depth therefrom. As readily understood the arrangement of a tubular spool of wire 502 on the spool 500 between the two end flanges 536 and 538 thereof will cause a more or less bias from the spring 532 depending upon, in which of the slots 542, 544 or 546 the arm 528 is arranged as a cross bar.

The rotatably arranged ring 196 is composed of two portions. A main portion 550 (Fig. 3) comprising substantially three-fourths of the circle and another portion 552 hingedly connected thereto by means of a hinge 554 and comprising the remaining quarter of the circle. The two portions of the ring may be closed by engaging their ends. The end of the main portion 550, which in Fig. 3 is shown partly in section is bifurcated, only the rear part 556 of the fork being shown in Fig. 3. The bottom of the fork has at 558 an inclined surface, which is not radial. Between the two forks a small pin 560 is arranged. The end of the ring portion 552 is shaped to engage the bifurcated end of the main portion by means of a projection 562 having a small recess 564 to fit round the pin 560. To keep the two portions locked together a locking lever 566 is mounted pivotably by means of a rivet 568 on the interior side of the ring portion 552. The locking lever has at one side a small recess 570 adapted to engage under the head 572 of a small rivet arranged on the interior side of the main ring portion 550. As will be readily understood this enables a locking with maintaining a smooth outer surface of the ring independent of the locking.

In operation the machine described above works as follows:

In the following operation the production of a wreath ring of straw is presupposed, but it will readily be understood that the machine is not restricted to the production of rings but can easily be used for producing of objects of any other form.

Initially the ring 196 is closed (Fig. 1) and the

lever 48 pressed down to its lower position with the projecting portion 84 of the hook 82 snapping over its end. The handle 312 of the lever 300 is then pressed down to engage the driving roller 298 (Fig. 13) with the exterior surface of the ring 196 either before or after switching on the motor 262 (Fig. 18) by means of the switch 270 (Fig. 1). Then the handle 484 is moved in counterclockwise direction to engage the three pinions 360, 380 and 390 (Fig. 5) to set the three rollers 324, 326 and 328 in rotation. A suitable bundle of straw is then taken, corresponding in size substantially to the input opening 60 (Fig. 23) of the funnel 58 and pressed in thru the opening thereof, until the front portion of it is taken by the ribs of the rollers 324 and 328 (Fig. 6). The operator then only has still to supply substantially the same amount of straw continuously thru the funnel. Before the front part of the straw has reached the rollers the operator draws the end of the wire 502 (Fig. 3 and 23) down and winds it one or two times round the front portion of the straw. During the continuous operation the rotation of the ring 196 in connection with the step by step movement of the rollers 324, 326 and 328 (Fig. 1) will cause the continuous string of straw to be guided in the annular space between the two guide plates 128 and 144. When the end of the continuous string passes the output end it pushes the plate 182 away enabling the operator to guide it by hand the remaining part of its way. The operator takes care that he disconnects the feeding of straw so that the two ends will assemble and allows the connection of the two ends to pass once again thru the rollers to have a double wound joint. When the operator releases the handle 312 causing the rotatable ring 196 to stop and simultaneously also stopping the rollers 324, 326 and 328. Then also the handle 484 is released causing the roller 328 to be moved away from the two other rollers. If necessary the operator gives the ring 196 a part of the revolution to bring it in the position shown in Fig. 3 enabling him to open the ring. By releasing the handle 484 also the projecting portion 84 of the hook 82 (Fig. 3) has been released, because the swinging of the double triangular plate 438, 490 (Fig. 9) carrying the roller 328 will cause the arm 104 to move in direction of the arrow shown in Fig. 9 pushing with its end the lower end of the pawl lever to release the end of the arm 48 (Fig. 3) enabling it to spring up influenced by the spring 68. Then the operator can easily lift up the finished straw ring after having cut the wire 502 and take the straw ring out to start over the operation again by closing the parts putting in a fresh end of a straw bundle securing the wire 502 (Fig. 23) thereto and then starting the machine again.

No efforts are necessary to operate the machine and the automatic feeding mechanism in connection with the guiding plates 128 and 144 enables an unskilled worker to operate the machine after a few hours' instruction to produce a uniform product.

In practice many different sizes of wreath rings are used. To enable the machine to be adjusted to different sizes the funnel lever 48, the three rollers 324, 326 and 328 and the guides 128, 144 are mounted to be easily detachable in order to be replaced by similar parts of other dimensions.

In Figs. 20, 21 and 22 three sets of such accessories of different sizes are shown each member being designed by similar references as in the

other figures with an index letter corresponding to the capital letter shown for each size. In order to shift the parts only the following operations are needed. To shift the funnel 58 only the hinge pin 52 (Fig. 3) has to be withdrawn allowing the funnel lever 43 to be removed and a new funnel lever to replace it. To shift the rollers only the three wing nuts 358, 378 and 388 (Figs. 5, 6 and 14) have to be loosened and removed allowing the three rollers 324, 326 and 328 to be lifted and replaced by new rollers of other size. As already explained the guiding members 128 and 144 are replaced by loosening the respective clamping members cooperating with the projecting arms attached to the guiding members along their lower edges.

Fig. 2 shows the left hand corner of the table with a modified embodiment. Instead of a hand lever start operation foot control is here used. The lever 300 is cut off just after the spring 302 and near the spring a rod 301 is arranged having its other end connected to a pedal 303 at its end 305 the other end of the pedal being pivotably arranged about a shaft 307 between the two small brackets 309 and 311 carried by a plate 313 connected to the leg 22.

In the embodiment shown in Fig. 12 a modification of the driving mechanism shown in Figs. 5 and 6 is illustrated. Here the crank 412, 414, 416 is eliminated. The spindle 402 terminates under the arm 410 and carries here a universal joint 403, which is connected to a short, vertical spindle 405 carrying at its top a substantially circular disc 407. This disc is extending from its underside provided with a recess 409 forming a part of a cylinder. Above this recess a projection 411 is provided having a downwardly extending pin 413 adapted to engage with slots 415 in a Geneva movement cross 417 thus imparting to the shaft 342 for the roller 324 a step by step movement in well known manner. In the modified embodiment shown in Fig. 19 another form of outer guiding member instead of that shown at 144 in Fig. 1 is illustrated. The outer guide here designed as 145 simply consists of a cylindrically curved plate corresponding to the interior guide 128, which for many purposes will be fully satisfactory to enable operation.

As it will be understood the invention is not limited to the use of circular guides. The machine can also of course be used without any guides at all for the purpose of making long continuous length of straw columns surrounded by spiral wound string of wire.

It will also be understood that the details of the machine can be modified in different respects within the scope of the invention, which is only limited to the combination of features set forth in the appended claims. So for instance Fig. 24 shows a modification of the roller driving mechanism as compared to that shown in Figs. 5, 6, 10 and 11.

According to this embodiment the rocking movement of the lever 426 (Fig. 5, Fig. 24) is effected by an arm mounted for reciprocating movement and operated by a cam member on the surface of the rotatable ring 196.

To this effect the lower portion 350 (Fig. 14, Fig. 24) of the roller support has a downwardly extension bracket 590 with a vertical portion below and in spaced relationship to the portion 350. The end of the vertical portion is provided with a portion 592 of increased cross section, in which is provided a slot or the like forming a guide for a lever 594 mounted for reciprocating movement

and extending with its one end at 596 against the rotatable ring 196. At this end of the lever 594 a roller 598 is mounted for instance in a bifurcated end portion of the lever 594. The other end of the lever 594 is provided with another roller 600 adapted to engage the end of the rocking lever 426. To keep the lever 426 in engagement with the roller ended arm a spring 602 is provided between the end of the lever 426 and the end of a pin 604 on the portion 592. The spring also serves to keep the roller 598 in engagement with a lateral surface on the ring 196. In this embodiment this lateral surface of the ring is provided with a cam surface member 604. From Fig. 24 it will readily be understood that when the ring 196 rotates in the direction of the arrow shown the lever 594 will be pushed towards the right side thereby swinging the lever 426 in clockwise direction seen from the bottom imparting by 20 the mechanism connected with said lever a stepwise movement to the rollers to give a straw bundle clamped therebetween a stepwise forward movement. When the roller 598 is released from the cam surface the parts will by means of the spring 602 automatically be retracted to their initial position.

While in the foregoing a funnel shaped notch or aperture 58 has been described for the purpose of feeding a straw bundle thru the center of the rotating ring to be gripped behind the ring by the rollers it will be understood that it will also be possible within the scope of the invention instead of such funnel shaped opening to duplicate on the front side of the ring the roller mechanism to form a similar construction at the input side as that shown and described behind the ring.

Hereby the straw bundle will already at the input end be clamped and fed thru the rotating ring. In such case of two opposite roller mechanisms the embodiment shown in Fig. 24 is especially advantageous, because the cam members, which in that event must be provided on both lateral sides of the ring 196 can be arranged 45 opposite each other so that the two reciprocating levers serving to operate the roller driving mechanism will counterbalance each other and thereby do not give rise to any lateral reaction forces of the ring.

It will be understood that the machine described can be used as well to produce linear straw beads as straw rings, in which latter event the circular guiding members serve to form between the output end and the input end a substantially circular guiding path. In the case of the production of linear straw beads the guiding members will have to be removed from the table surface.

It has been found that even in the production 60 of straw rings the circular guiding members can be avoided in the case that the rollers are arranged to feed the straw bundles with a higher velocity on one side than on the other side. Thus for instance as in the case of Fig. 1 the two rollers 324 and 326 can be of increased diameter, while the roller 328 is of decreased diameter. When the three rollers are driven at the same velocity the circumferential speed of the two 65 rollers having increased diameter will be higher than that of the roller having decreased diameter giving rise to an uneven action on the straw bundles whereby it will automatically from the output end form itself like a ring. In such event 70 the interior guiding member 128 will still be of

use for securing a uniform interior diameter of the rings produced.

I claim:

1. In a machine for producing straw rings, a table, a detachable arm having a substantially funnel shaped aperture having a wide opening and a narrow opening pivotably attached to the top surface of said table, resilient means operable to raise said arm to an inclined position relatively to said table, locking means to keep said arm in position adjacent the surface of said table, an aperture in said table surface adjacent said arm at the narrow funnel opening side thereof and extending in both directions from said narrow funnel opening, a ring rotatably mounted thru said aperture having its center of rotation substantially in alignment with said funnel opening and carrying thereon a wire reservoir, a portion of said ring hingedly connected to the other portion thereof, locking means adapted to lock said two ring portions, at least two rollers mounted for rotatable movement on the top surface of said table adjacent said aperture therein and in spaced relationship opposite said narrow funnel opening, substantially circular guiding members detachably mounted on the top surface of said table and extending from said rollers to form an annular guiding channel substantially from said narrow funnel opening to said wide funnel opening, means for moving said rollers relatively to each other to clamp therebetween a straw bundle put in thru said funnel opening, means for imparting a continuous rotation movement to said ring and means for intermittently moving said rollers to impart a stepwise forward feeding to said straw bundle clamped therebetween into and thru said annular guiding channel.

2. In a machine for producing straw rings, a table having a top surface, a structure forming a notch and adapted to be movably connected to said table so as to form an aperture by engaging said notch against the table surface, means to keep said structure in the position in which said notch engages said table surface, means operable to move said structure to a position in which said notch is spaced from said table surface, an aperture extending thru said table substantially adjacent said structure, a ring rotatably mounted in said aperture having its center substantially in alignment with said notch in said structure and carrying a wire reservoir, said ring being composed of at least two portions hingedly connected to each other, locking means adapted to mutually lock said ring portions, a pair of substantially circular guiding members detachably mounted on the top surface of said table and forming between them a substantially circular guiding path extending between the two sides of said notch, when said structure is engaging the table surface, said path arranged to bypass said rotatably mounted ring.

3. In a machine for producing straw beads, a table, an arm having substantially funnel shaped notch extending from one side thereof movably arranged relatively to the top surface of said table, means to keep said arm in a position with said notch adjacent the surface of said table, means operable to raise said arm to a position, in which said notch is spaced from said table surface, an aperture in said table surface adjacent said arm at the narrow funnel opening side thereof and extending in both directions from said narrow funnel opening, a ring rotatably mounted thru said aperture having its center of rotation substantially in alignment with said funnel open-

ing and carrying thereon a wire reservoir, a portion of said ring hingedly connected to the other portion thereof, locking means adapted to lock said two ring portions, at least two rollers mounted for rotatable movement on the top surface of said table adjacent said aperture therein and in spaced relationship opposite said narrow funnel opening, substantially circular guiding members detachably mounted on the top surface of said table and extending from said rollers to form an annular guiding channel substantially from said narrow funnel opening to said wide funnel opening, means for moving said rollers relatively to each other to clamp therebetween a straw bundle put in thru said funnel opening, means for imparting a continuous rotation movement to said ring and means for intermittently moving said rollers to impart a stepwise forward feeding to said straw bundle clamped therebetween into and thru said annular guiding channel.

4. In a machine for producing straw beads, a table, an arm having a substantially funnel shaped aperture movably arranged relatively to the top surface of said table, means operable to hold said arm in a position adjacent the surface of said table and means for releasing said arm from said position, an aperture in said table surface adjacent said arm extending in both directions from said funnel shaped aperture, a ring rotatably mounted in said aperture having its center of rotation substantially in alignment with said funnel shaped aperture and carrying thereon a wire reservoir, a portion of said ring hingedly connected to the other portion thereof, locking means adapted to lock said two ring portions, at least one rotatably mounted roller on the top surface of said table adjacent said aperture there-in opposite one side of said narrow funnel opening, another roller rotatably mounted in spaced relationship thereto opposite the other side of said narrow funnel opening, a substantially circular guiding member detachably mounted to the top surface of said table and extending from said first mentioned roller, a further substantially cylindrical guiding member detachably connected to the top surface of said table extending substantially from said last mentioned roller to a point near the wide opening of said funnel to form with said first mentioned guiding member a substantially annular guiding channel, means for moving said rollers relatively to each other to clamp therebetween a straw bundle put in thru said funnel opening, means for imparting a continuous rotation to said ring and means for intermittently moving said rollers to impart a stepwise forward feeding to said straw bundle clamped therebetween into and thru said annular guiding channel.

5. In a machine for producing straw beads, a table having a top surface, an arm arranged to make a pivotable movement relatively thereto and having extending from the surface adjacent said table surface a substantially funnel shaped notch, releasable means to hold said arm in a position, in which said notch engages said table surface to form therewith a funnel shaped aperture, means operable to move said arm to a position in which said notch is spaced from said table surface, an aperture adjacent said arm extending in opposite directions from said notch in the position where said arm engages said table surface, a supporting structure extending above and below said table in alignment with said aperture therein and carrying supporting rollers, a ring rotatably mounted supported by said rollers and

having its center substantially in alignment with said notch in the position thereof, in which said arm engages said table surface, said ring comprising at least two portions arranged for relatively mutual movement to allow said ring to be opened, means for mutually locking said two ring portions, means for mounting a wire spool on said ring, a driving roller movably arranged to engage the circumference of said ring, power means for driving said roller, means operable at will for keeping said driving roller in engagement with said ring to impart a continuous rotation thereon, said operable means further being releasable, at least two releasable rollers mounted for rotatable movement extending thru the top surface of said table adjacent said aperture therein and in spaced relationship opposite said funnel shaped notch, said rollers forming between them a passageway, a gear mechanism for rotating said rollers in a direction to impart a forward movement to a straw bundle clamped in the passageway between said rollers, means for intermittently driving said roller driving gear mechanism responsive to the rotation of said ring, means operable at will to move at least one of said rollers to a position spaced from said other roller to release the straw bundle clamped therebetween, said operable means also being adapted to release said arm having said funnel shaped notch from its position engaging said table surface, a pair of substantially circular guiding members detachably arranged on said table surface in spaced relationship to form therebetween, a substantially circular guiding path extending between the output side from said rollers and the input side of said funnel shaped notch bypassing said rotatably arranged ring.

6. In a machine for producing straw beads, a table having a top surface, an arm arranged to make a pivotable movement relatively thereto and having extending from the surface adjacent said table surface, a substantially funnel shaped notch, releasable means to hold said arm in a position, in which said notch engages said table surface to form therewith a funnel shaped aperture, means operable to move said arm to a position in which said notch is spaced from said table surface, an aperture adjacent said arm extending in opposite directions from said notch in the position where said arm engages said table surface, a supporting structure extending above and below said table in alignment with said aperture therein and carrying supporting rollers, a ring rotatably mounted supported by said rollers and having its center substantially in alignment with said notch in the position thereof, in which said arm engages said table surface, said ring comprising at least two portions arranged for relatively mutual movement to allow said ring to be opened, means for mutually locking said two ring portions, means for mounting a wire spool on said ring, a driving roller movably arranged to engage the circumference of said ring, power means for driving said roller, means operable at will for keeping said driving roller in engagement with said ring to

impart a continuous rotation thereon, said operable means further being releasable, at least three rollers mounted for rotatable movement extending thru the top surface of said table adjacent said aperture therein and with two of said rollers in spaced relationship from said third roller opposite said funnel shaped notch, said rollers forming between them passageway, a gear mechanism for rotating said rollers in a direction to impart a forward movement to a straw bundle clamped in the passageway between said rollers, means for intermittently driving said roller driving gear mechanism responsive to the rotation of said ring, a lever system to move at least one of said rollers to a position spaced from said other rollers to release the straw bundle clamped therebetween, said lever system having means to release said arm having said funnel shaped notch from its position engaging said table surface, a pair of substantially circular guiding members detachably arranged on said table surface in spaced relationship to form therebetween a substantially circular guiding path extending between the output side from said rollers and the input side of said funnel shaped notch bypassing said rotatably arranged ring.

7. In a machine for producing straw rings, a table, an arm having a substantially funnel shaped notch extending from one side thereof movably arranged relatively to the top surface of said table, means to keep said arm in position with said notch adjacent the surface of said table, means operable to raise said arm to a position, in which said notch is spaced from said table surface, an aperture in said table surface adjacent said arm at the narrow funnel opening side thereof and extending in both directions from said narrow funnel opening, a ring rotatably mounted thru said aperture having its center of rotation substantially in alignment with said funnel opening and carrying thereon a wire reservoir, a portion of said ring hingedly connected to the other portion thereof, locking means adapted to lock said two ring portions, substantially circular guiding members detachably mounted on the top surface of said table and extending to form an annular guiding channel substantially from said narrow funnel opening to said wide funnel opening and power means for imparting a continuous rotation movement to said ring.
